UNITED STATES PATENT OFFICE.

RAYMOND D. FOLTZ, OF EAST ORANGE, NEW JERSEY, ASSIGNOR TO M. H. DETRICK COMPANY, OF CHICAGO, ILLINOIS, A CORPORATION OF ILLINOIS.

STOKER FURNACE CONSTRUCTION.

Application filed July 10, 1924. Serial No. 725,143.

To all whom it may concern:

Be it known that I, RAYMOND D. FOLTZ, a citizen of the United States, residing at East Orange, in the county of Essex and State of New Jersey, have invented certain new and useful Improvements in Stoker Furnace Constructions, of which the following is a specification.

This invention relates to improvements in furnaces of the type employing adjustable fuel gates or the like, such as for stokers of the chain grate type. In such installations there is a very intimate and important cooperation between the stoker and the furnace arch portion, which is variously known as the ignition arch, coking breast, combustion arch, etc., as proper ignition and combustion of the fuel is dependent upon the conjoint functioning of those parts. Among other essential considerations, it is vital to proper operation of the furnace, that proper control be maintained of the quantity of fuel fed, and the arch be maintained in proper condition to secure quick ignition, adequate coking, and thorough combustion of the fuel. The conditions under which such installations are operated are very trying, due to the extremely high temperatures to which they are subjected, the prolonged periods through which they are in continuous operation, and the almost universal demand for operation at very high capacities.

The general purpose of the present invention is the provision of certain improvements in the construction of such installations which will contribute to the durability of the feed and ignition controlling portions of the installation, and facilitate repair and replacements when such become necessary.

Another purpose is the provision of improvements in the structure which are calculated to contribute to accuracy in the control of the fuel feed.

Other and further objects and advantages of the invention, as well as a more specific understanding of those above specified, will be indicated hereinafter, or ascertainable from the appended claims and the drawing forming a part of this specification. For the purpose of this application I have shown one fashion in which the invention may be embodied, but it is to be understood that the same is here presented for the purpose of illustration only, and hence is not to be accorded any effect calculated to limit the in-

vention which I purport to secure by Letters Patent, short of its true and most comprehensive scope in the art.

In the drawing:

Fig. 1 is a partly diagrammatical illustration in the nature of a part sectional elevation through the front portion of an installation which includes a chain grate stoker, and

Fig. 2 is a detail in the nature of a front sectional elevation taken on substantially the line 2—2 of Fig. 1.

Referring immediately to the illustrative embodiment shown in the drawing, let it be understood that the reference character 10 designates a side wall of the furnace chamber into which fuel is supplied by a chain grate stoker, the movable grate portion of which is illustrated at 11. Over the fuel inlet is arranged an ignition arch. This is carried on a beam 12 which is supported at the sides of the furnace, and includes a number of suspension frames 14 which are hung from said beam in collateral relationship across the furnace. The frames have tile retaining members 15 in the form of flanges, which support refractories in proper association to form a continuous heat-resisting arch portion depending above and adjacent the fuel inlet and overhanging that portion of the grate. These refractories, as in the case of those designated 16, may be supported by direct engagement with the tile-retaining members 15, or through the instrumentality of supplemental hangers 17, as in the case of the refractories 18. These supplemental hangers are in the nature of hooks demountably supported on the members 15 and slidable therealong and affording the laterally projecting parts 17^a which engage in recesses of the refractories 18. In this fashion the respective refractories are individually suspended so that each has a certain freedom of movement relative to the others, and is thus capable of accommodating itself to expansion and contraction incident to the heating and cooling of the furnace. The frames 14 also have vertical channel portions at the front, which retain the bricks 19 forming a rear wall portion for the stoker hopper 20, said bricks 19 being retained at the bottom by the lateral flanges 21 on the frames 14.

The hopper 20 directs fuel, by gravity, onto the apron 22, which conveys it onto the

chain grate 11 as the latter is transmitted inwardly in the fashion well known in the art. The thickness of the fuel bed, or the amount of fuel thus fed into the furnace, is thus controlled by the speed of the grate and by the size of the feed opening as determined by the position of the fuel gate. The fuel gate is formed of a metallic frame member 24 extending across the stoker and supporting a facing of refractories 24^a on the side toward the furnace chamber. It is suspended and guided for vertical sliding movement in such relationship as to control the height of the fuel inlet. Its operation and adjustment in that respect are controlled by suitable mechanism, here diagrammatically illustrated by the hand wheel 25 which drives beveled pinions 26 to rotate gear 27 which transmits rack 28 attached to the gate. Due to the necessary association of both the gate and the lower refractories of the ignition arch with the fuel inlet, the gate must operate in close proximity to the arch refractories. It frequently occurs, when the gate remains for a considerable time at a certain adjustment, that it becomes cemented to the adjacent arch refractories by the slag which forms on the exposed surfaces in the combustion chamber. This not only interferes with subsequent adjustment of the gate, but frequently results in the breaking of either the gate or the arch refractories incident to such adjustment. Sometimes also, the arch becomes warped from the heat, so that upon adjustment of it, injury may result to its refractory facing or the adjacent arch refractories. In order to avoid such contingencies, and also to facilitate the repair or replacement of refractories in the gate and the arch, I equip the frames 14 with demountable bearing members 29. Each of these castings is in the form of a plate of a width approximating that of the arch refractories on the frame, and of such height that it will extend well down in front of the refractories when the bearing member is attached to the frame as intended. This connection is accomplished by means of a bracket 29^a formed on the rear side of the bearing member at its top and extending at right angles to the plate portion and shaped to fit against the web of the frame member 14 and in abutment with the flange 21. Here it is secured by means of a bolt 30, its rearward surface abutting the forward margin of the web of the frame 14. In this disposal the bearing members form an intervening retaining guide between and cooperating with the gate and the lowermost arch refractories. They hold the arch refractories in place against gravity, the abutment of the bracket 29 against the flange 21 preventing their forward rotation on their connecting bolts, and thus they relieve the gate

of pressure from the arch. They also support the inward pressure of the gate, which may result in part from the weight of coal in the hopper 20, such inward thrust from the gate being transmitted by the members 29 directly to the frames 14, by virtue of their abutment. This relieves the arch refractories of any pressure from the gate. Furthermore, these bearing members keep the gate refractories spaced away from the arch refractories so that there is not the opportunity for them to slag together. Adjustment of the gate is facilitated and interference resulting from warping of the gate is minimized. One important advantage resulting from this construction is the ease with which the lower arch refractories may be replaced. In such proceeding it is necessary simply to lower the gate to its limit, then remove the bolts 30 from the frames on which the replacement is required, and remove the bearing members outwardly. This permits removal and replacement of the refractories from the lower portion of the selected frames, without disturbance of any of the other refractories. It may be desirable to aperture the plate portions, as illustrated, to permit a certain amount of ventilation of the tile slots as a precaution against over-heating of the tile-retaining members or supplementary hangers.

From the foregoing it will be observed that this improvement contributes materially to accuracy, effectiveness and convenience in the supply and ignition of the fuel.

What I claim is:

1. In a furnace installation including the adjustable stoker gate and adjacent ignition arch, a frame supporting arch refractories and a bearing member demountably secured to the frame for engagement with refractories on one side and the gate on the other side.

2. In a furnace installation including the adjustable stoker gate and adjacent ignition arch, a frame supporting arch refractories and a bearing member demountably secured to the frame for engagement with refractories on one side and the gate on the other side, said bearing member having engagement with the frame to prevent its rotation in either direction.

3. In a furnace installation including the adjustable stoker gate, a frame supported adjacent the gate, refractories having slideable mounting on the frame and a bearing member demountably secured to the frame and depending therefrom between the refractories and the gate.

4. In a furnace installation, the combination of a frame, refractories slidably supported thereon, and a bearing member demountably secured to the lower portion of the frame for engagement with refractories

- to prevent their sliding off the frame, said bearing member having abutment with the frame preventing its rotation thereon by the refractories.
5. In a furnace installation including the adjustable stoker gate, frames depending collaterally adjacent the gate, tiers of refractories supported independently by the respective frames and having sliding movement thereon, and a separate bearing member demountably secured to each frame in position to prevent displacement of the refractories thereon toward the gate or movement of the gate into contact with such refractories, said bearing members accommodating relative movement of the frames.
6. In a furnace installation, the combination of the depending arch frame, refractories slidably supported thereon, a bearing member demountably secured to the lower portion of the frame for engagement with refractories thereon to prevent their sliding off, said bearing member being provided with an aperture permitting access of air therethrough to the frame.

In testimony whereof I have hereunto subscribed my name.

RAYMOND D. FOLTZ.
